UNITED STATES PATENT OFFICE.

HARRY W. NEAL, OF INDIANAPOLIS, INDIANA, ASSIGNOR TO HALL-NEAL FURNACE COMPANY, OF INDIANAPOLIS, INDIANA, A CORPORATION OF INDIANA.

DAMPER CONTROL FOR FURNACES.

Application filed December 24, 1923. Serial No. 682,519.

To all whom it may concern:

Be it known that I, HARRY W. NEAL, a citizen of the United States, residing at Indianapolis, in the county of Marion and 5 State of Indiana, have invented new and useful Improvements in Damper Controls for Furnaces, of which the following is a specification.

This invention relates to improvements 10 in means for the control of the damper in the smoke pipe of hot air furnaces which pipe is generally located at or near the rear of the furnace where it is not handily accessible from a front position of the care-taker, 15 and the object of the invention is—

First, to provide means, manually operated from a position in front of the furnace, for opening and closing the smoke pipe damper wherever located, and for retaining 20 the damper at any desired position.

Second, to provide means for locking the damper at any given position of adjustment.

Third, to provide an indicator at the front 25 of the furnace which will always show the position of the damper, and

Fourth, to provide a device of the above character that is inexpensive to manufacture, easily installed at any time on furnaces now in common use, simple in its operation and durable.

I accomplish the above, and other objects which will hereinafter appear and which will be pointed out in the claims, by the mechanism illustrated in the accompanying 30 drawing, in which—

Fig. 1 is a front elevation of a portable hot-air furnace provided with my invention. Fig. 2, is a side elevation of same with a portion of the smoke pipe in vertical 40 section to disclose the damper mounted therein. Fig. 3 is a horizontal section of one side of the furnace taken on the line 3—3 of Fig. 2 showing my invention, and Fig. 4 is a fragment of a furnace casing with my 45 damper-control mechanism installed.

Like characters of reference indicate like parts throughout the several views of the drawing.

I have illustrated my invention as applied to a cylindrically shaped portable hot-air furnace of usual and well known construction, in which a fire-pot and combustion chamber 5 has a cast-iron front 6, with a fuel door 7 and dash door 8, a smoke dis-

charge pipe 9 controlled by the well known 55 butter-fly valve 10, having a valve-stem 11, here vertically placed and projecting above the pipe for the attachment thereto of a rocker-arm 12, by which the stem and valve are moved.

A cylindrical sheet metal casing 13 is attached by angle-bar 14 to one of the outside vertical corners of the front 6, and curving thence around the member 5, is attached to the corresponding opposite corner of the 65 front 6. It is separated from the member 5 to provide the usual hot-air space 14'. As here shown, the sheet metal casing is formed in a plurality of sections joined by vertical interlocking seams 15, wherein the sheets are 70 held by bolts 16 from longitudinal displacement, and these seams are turned outwardly of the casing in the form of vertical and radially disposed flanges.

Bolted to one of the front angle-bars is a 75 bracket 17, having a horizontally elongated slot 18, and brackets 19 and 20 are similarly bolted to the seam-flanges 15, on the same side of the furnace as said angle-bar. Instead of a slot, each of the brackets 19 and 80 20 is provided with a round hole, in which, and also in the slot 18, a curved rod 21, is mounted. This rod 21 is of spring metal, preferably steel, so bent as to normally assume a curve of smaller radius when unrestrained than that compelled by the openings in the brackets in which it is mounted, with the result that it bears against the inner end of the slot 18 when the rod is unrestrained, but which can be sprung out to 85 the outer end of the slot to the position shown in dotted line in Fig. 3.

One end of the rod 21 is connected by a link 22, with the outer end of the rocker-arm 12, whereby, by a longitudinal movement of 90 the rod, the rocker-arm 12 will be correspondingly moved to rock the valve or damper 10.

To facilitate the longitudinal movement of 100 rod 21, it is provided with a handle 24 at its front end, here shown as a loop bent out of the material of the rod and standing radially of the furnace. The end 25 of the rod is continued inwardly of the loop into contact with the front 6, against which it is held normally by the spring-tension of the rod 21. The front 6 preferably has a series 105 of corrugations 26, and the tip of the end

25 is tapered to a cone to engage with said corrugations and hold the rod in any given longitudinal adjustment.

In the operation of my invention, assuming that the rod 21 is in the closed position of the damper as indicated in Fig. 4, then, to open the damper, the end 25 is disengaged by manually pulling outwardly on the handle 24. This is permitted by the slot 18, and while the end is disengaged the rod 21 is pulled toward the position marked "open"—all of the way, or for any fractional part of the distance, as may be desired, and released, whereupon the rod will spring the end 25 again into engagement with the corrugations 26. The damper will be correspondingly opened by reason of the above-described connection between it and the rod 21, and a reverse operation will partially or entirely close the damper, as the operator may elect.

Having thus fully described my invention, what I claim as new and wish to secure by Letters Patent of the United States, is—

25 1. The combination, with an upright cylindrical furnace having front doors and a rear smoke-pipe, of a damper in the pipe, means for operating the damper comprising a resilient push and pull rod curved around one side of the furnace and having a front end portion normally contacting the furnace

by a spring-action of the rod, and a series of corrugations on the furnace in the path of said front contacting portion to limit the free pull and push movement of the rod by engagement with the spring-pressed end. 35

2. The combination, with a furnace having a sheet metal casing in a plurality of sections joined by seams forming outside vertical flanges, of a smoke-pipe, a butterfly damper in the pipe, a stem, a rocker-arm attached to the stem, a curved spring-bar passing from rear to front of the furnace through holes in said flanges on that side of the furnace where the rod is placed, all of 40 said holes making a close sliding fit with the bar except the front one which is slotted horizontally, the tension of the spring-bar holding the bar normally at the inner end of said slot, the front end of the spring-bar having an extension normally contacting the furnace by the spring action of the bar, and a series of indentations on the furnace to engage with the end of the bar extension and hold the longitudinal adjustment of the 45 bar, and a link connecting the rear end of the spring-bar with the rocker-arm of the damper-stem. 50

Signed at Indianapolis, Indiana, this 21st day of December, 1923.

HARRY W. NEAL.
